No. 11,654

FEB 17, 1880

UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,654, dated February 17, 1880.
Application filed January 17, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design consists, first, of a ground ornamented by finely wrought lines, dots, and stars; secondly, broken Grecian bars a a a; and, thirdly, sprays of flowers b b b between the bars, all as shown.

I claim—

The design for a carpet, substantially as 15 shown and described.

In testimony whereof I have signed my name to this specification, in the presence of two subscribing witnesses, this 15th day of January, 1880.

THOMAS J. STEARNS.
